ELECTRON DISCHARGE TUBE

Adolph A. Thomas, New York, N. Y., assignor to
 Radio Corporation of America, New York, N. Y.,
 a corporation of Delaware

Application May 16, 1936, Serial No. 80,078

14 Claims. (Cl. 250—27.5)

My invention is for an electron discharge tube of novel construction and possessing certain practical advantages over prior devices of this type. One object of this invention is to improve the manufacture of electron tubes having a metal envelope by reducing the number of parts and facilitating the mounting and assembly of the various elements, particularly as regards the insulation of the electrode-supporting rods or lead-in wires. Another object of my invention is to improve the operation of metal electron tubes, especially those used in radio apparatus, by eliminating or greatly lessening the tendency of the metal envelope to give off gas from its inner surface.

The all-metal radio tubes which have recently come into use comprise an outer metal shell and a metal base disk sealed together. This metal disk carries the conducting rods or lead-in wires connected to the electrode assembly, and each wire must be carefully insulated from the metal of the disk. According to present practice, this insulation requires an alloy eyelet welded around a hole in the metal disk, there being a hole for each wire, and the wire passing through the eyelet is sealed thereto by a small thin sleeve of glass which constitutes the only insulation between the lead-in wire and the metal disk. Aside from the cost of thus insulating each wire separately from the metal walls of the tube, there is the danger that any one of these thin glass sleeves might crack or a current of high voltage might leap across a glass sleeve to the grounded metal of the base disk and put the tube out of commission.

Further, in testing the behavior of all-metal radio tubes during operation, it has been found that the inner metal surface of the envelope or shell has a tendency to give off gases which reduce the efficiency of the tube or otherwise interfere with its proper functioning. Thus, although metal radio tubes as heretofore made have the advantage of mechanical strength and electrical self-shielding as compared with the old glass tubes, the use of a metal envelope and base has the double disadvantage of increasing the manufacturing cost of the tube and of gradually deteriorating the vacuum in the metal-walled chamber.

To overcome the afore-mentioned and other disadvantages inherent in prior all-metal radio tubes, I have devised a new electron tube consisting of a metal shell and an insulating base disk of vitreous material which supports the lead-in wires and automatically insulates them. The

metallic shell or envelope and the insulating base disk are sealed together by an interposed ring of glass which is fused into place to form a permanent vacuum-tight weld of ample mechanical strength. The lead-in wires or rods connected to the electrode assembly pass through holes in the insulating disk to which they are sealed by small cylinders of fused glass, and no separate insulation of these wires is necessary. The insulating disk, being sufficiently thick and strong, may also support the outer contact pins of the tube, so that no separate base member for the pins is needed, as in prior tubes. This base disk may be molded or pressed of glass having a low expansion coefficient, or of vitreous ceramic material like porcelain, which is amply strong when thick and is practically unaffected by heat. The inner surface of the metal shell is preferably electroplated to provide a smooth dense wall adapted to prevent (or at least minimize) the occlusion and subsequent liberation of gases. The metal shell at its base encloses the insulating disk and fully protects it, so that the tube is practically as strong as if made wholly of metal, yet is cheaper to make and more satisfactory in its operation.

The various novel features and advantages of my invention will be understood from a description of the accompanying drawing, in which

Fig. 1 represents a vertical section of an electron discharge tube made according to my invention;

Fig. 2 shows how the metal shell and the insulating disk are sealed together;

Fig. 3 is a cross-section on line 3—3 of Fig. 1;

Fig. 4 shows a modified form of tube;

Fig. 5 is a cross-section on line 5—5 of Fig. 4;

Fig. 6 is an enlarged fragmentary view showing how the lead-in wires and contact pins are sealed to the insulating disk; and

Figs. 7—8 show different ways of mounting the contact pins in the insulating disk.

Referring to Fig. 1, the outer structure of the electron tube consists of two main parts, a cylindrical shell or envelope 10 of sheet metal and a base disk 12 of insulating material of the vitreous type, such as glass or porcelain. The metal shell 10 may be of steel, nickel, duralumin, or an iron-nickel alloy with a low expansion coefficient,—to mention only a few of the commercially available metals. Personally I regard steel as the best metal to use on account of its strength and cheapness, but an iron-nickel alloy of approximately 63% iron and 37% nickel has certain advantages, as I shall point out later.

The base end of metal shell 10 is formed with an outer lateral shoulder 13 and a cylindrical flange 14, which preferably has an outwardly flaring edge 15 and terminates in an inwardly turned rim 16. The parts 13-16 form an annular recess 17 which is completely filled by a seal 18 of glass or similar material fused in position and uniting the vitreous disk 12 to the metal shell 10 by a strong vacuum-tight joint. The disk 12 is preferably formed with a peripheral recess 19 to provide a circular shoulder 20 which locks the disk in the fused mass of the sealing ring 18. The inturned rim 16 on the lower end of metal shell 10 locks the seal 18 permanently in place.

It should be noted that the fused sealing ring 18 contacts the adjacent walls of parts 10 and 12 along wide areas, thereby producing a weld of ample strength to unite the metal shell 10 and the insulating disk 12 into a substantially integral vacuum-tight enclosure. The rim 16 of metal shell 10 encloses the edge of seal 18 for protection, this rim being preferably embedded in the fused seal to make it flush with the underside of the seal and disk 12. In other words, the underside of the tube may be a perfectly flat surface which permits the tube to be firmly mounted on a flat support.

Fig. 2 illustrates a simple method of fusing the glass ring 18 in position. The metal shell 10 is held upside down in a cylindrical support 21 suitably mounted for slow rotation, the shoulder 13 of the shell resting on the top rim 22 of the support. The vitreous disk 12 (carrying the electrode assembly) is placed centrally over the inverted shell 10, the edge of the disk resting on shoulder 13 of the shell. The glass sealing ring 18 (cut to the right width from a glass cylinder) is placed in the annular recess 17 formed between the flange 14 of shell 10 and the periphery of disk 12. As the support 21 is rotated, gas jets 23 heat the metal flange 14 and the glass ring 18, which melts in the final heating stage and flows into the recess 17, completely filling it. The hardened mass of seal 18 remains in strong vacuum-tight adhesion to the adjacent walls of metal shell 10 and vitreous disk 12.

When the sealing operation is finished, an ejector 24 lifts up the tube for easy removal from support 21. The ejector 24, which may be a vertically movable rod or piston, engages the tubulation 25 formed integral with the dome-shaped top of metal shell 10. The tubulation 25 connects the interior of the tube with a suitable source of exhaust, and after the desired vacuum has been attained the tubulation is sealed off in any practical way, as will be understood without further explanation. The sealed tubulation or tip is shown at 25' in Fig. 1. If it is desired to conceal the tip 25' in the commercial embodiment of the tube, the top of shell 10 is formed with a depression 26 around the tip and this depression may be filled with suitable plastic material 27, which rounds off the dome of the shell and hides the exhaust tip. The filler 27 may be glass, an aldehyde condensation product, ceramic material, or the like. If this dome-shaped filler is colored, it may also serve as a trade-mark.

The vitreous disk 12 is sufficiently thick to support the lead-in rods or wires 28 and the contact pins 29 to which the lead-in wires are electrically connected. In the broad aspect of my invention, the electrode assembly in the tube may be of any suitable construction or arrangement, depending on the function of the tube, which may

be a detector, an amplifier, a rectifier, or operate for any other practical purpose. By way of example I have shown in Fig. 1 an electrode assembly E consisting of an electron-emitting filament or cathode 30, a grid 31, and a cylindrical anode 32, all arranged and mounted in the usual way. For simplicity of illustration I have shown the electrode assembly supported on the rods 28, but any other practical form of electrode support may be used. With this three-electrode assembly only four of the six contact pins 29 will be electrically connected to the electrodes. The vitreous disk 12 has as many holes 33 as there are lead-in wires 28 passing through it, and the contact pins 29 are in axial alignment with these 15 holes. The enlarged view in Fig. 6 clearly shows how each wire 28 and its associated contact pin 29 are mounted in disk 12. The hole 33 has a circular shoulder 34 on which the round head 35 of pin 29 rests. The pin is preferably hollow for 20 receiving the wire 28 in a close fit, and the two parts may be soldered together at the tip, as indicated at 36, to insure good electrical contact.

To seal each wire 28 and its pin 29 to disk 12, a small glass cylinder or sleeve 37 is placed 25 around the wire in hole 33 and heat is applied uniformly around the glass sleeve, as by gas jets 38, until the glass melts and completely fills the hole around the wire 28 and the head 35 of contact pin 29. The fused condition of the glass 30 sleeve 37 is shown at 37' in Figs. 1 and 2. I may form the disk 12 with an integral upstanding rim 39 around each hole 33 to hold the molten glass better in place and increase the depth of the seal. 35 The glass seal 37' unites the wire 28 to the insulating disk 12 in a vacuum-tight weld, and is sufficiently strong to hold the wire and its contact pin rigidly anchored in the disk.

Figs. 7 and 8 illustrate other ways of securing the contact pins 29 to the vitreous disk 12. In 40 Fig. 7 the head 35 of the pin is embedded in the disk while the latter is still plastic in the mold. That is to say, the contact pins are properly arranged in the mold, so that when the plastic material is poured in, the headed ends of the 45 pins become embedded in the mass. When the hardened disk is then removed, the metal pins are permanent structural parts thereof. In Fig. 8 the molded disk 12 is formed with a circular recess 40 and a larger undercut recess or groove 41. The 50 head 35 of pin 29 fits snugly in recess 40 and is locked in place by a ring 42 which fills the outer recess 41. The ring 42 may be glass, ceramic material, or any suitable cement. The glass seal 37' for wire 28 in Figs. 7 and 8 is formed as previously explained in connection with Fig. 6. One 55 advantage of attaching the contact pins 29 to disk 12 as shown in Figs. 7-8 lies in the fact that the pins are held in place independently of the glass seal 37', so that any axial thrust against 60 the pins in handling the tube is taken up by the disk itself instead of the glass seals that hold the lead-in wires.

The tube shown in Figs. 4-5 differs from that of Figs. 1-2 mainly in having the exhaust tip 43 sealed into the vitreous base disk 12 by an annular glass seal 44, which may be formed in the same way as the seals 37' of wires 28. The disk 12 may have an annular projection 44' to provide a greater depth for seal 44. The exhaust tip 43 65 may be glass or metal; and if glass, it is preferably enclosed in a small sheet metal cup 45, the flanged head of which is embedded in the molded disk 12 by a cement ring 46 in an undercut groove 47 at the bottom of the disk. The cup 45 may be non- 70 75

cylindrical or have an axial notch 48 adapted to receive a properly placed rib or lug in the tube socket to compel the correct mounting of the tube.

- 5 By putting the exhaust tip 43 in disk 12, the dome-shaped top 49 of the metal shell 10 is free to support a cap contact 50, which is used in certain types of radio tubes, as those familiar with that art will understand without more words.
- 10 The top 49 is provided at the center with an integral tubular extension or nipple 51, which terminates in a small funnel 52 with an opening for the conducting wire 53. The funnel 52 is filled with a fused seal 54 of glass or the like, which closes the top of the tube in a vacuum-tight joint. The metal cap 50 is secured over the nipple 51 by means of a suitable cement 55, which is an electric insulator, and the outer end of wire 53 is attached to the top of cap 50, which is completely insulated from the metal shell 10 by the inner glass seal 54 and the cement lining 55.

The electrode assembly E' in Fig. 4 comprises a heating filament 56, a cathode 57 in the form of a hollow refractory rod through which the filament extends and which is coated with electron-emitting material, an inner grid 58, a second grid 59, and an anode 60 in the usual form of a metal cylinder surrounding the other electrodes. A disk 61 of mica holds the upper ends of the electrode-supporting rods rigidly spaced, and a small insulating disk 62 spaces the lower ends of rods 63 that support the grid 59. The disk 62 is mounted on a metal plate 62' welded to rods 63. The lower end of conducting rod 64, which supports the inner grid 58, is embedded in disk 62 and the upper end of the rod is connected with wire 53. The tubular cathode 57 passes through disk 62 and is rigidly connected by a cross piece 65 to the supporting rod 66. The mica disk 61 is perforated to permit the exhaustion of air from the upper space of the tube. It will be understood that any other practical electrode assembly may be supported in the tube to carry out the prescribed function thereof.

45 The glass sealing ring 18 in Fig. 4 may be applied as shown in Fig. 2 and previously described. The cylindrical flange 67 of the metal shell 10 in Fig. 4 has a hollow bead 68 which locks the fused seal 18 in place, and the disk 12 is locked to the seal by the undercut groove 69. Any other practical means may be employed for mechanically locking the united parts 10-12-18 together aside from the adhesion of the seal to the metal shell 10 and the vitreous disk 12, whereby the vacuum-tight weld between those three parts is materially strengthened. What else was said about the seal 18 in Fig. 1 applies to the seal in Fig. 4 without the need of repetition.

I have mentioned that the insulating disk 12 may be of glass or a vitreous ceramic material like porcelain. If the disk is molded or pressed of glass, it is preferable to use a glass having a low coefficient of expansion, say of the order of 0.000004, which is one of the properties of the borosilicate glasses. A particularly strong glass for disk 12 is a heat-proof glass like that described in Sullivan and Taylor Patent No. 1,304,623 granted May 27, 1919, this glass having an expansion coefficient even lower than the figure just given. Porcelain contains enough of a vitreous or glassy matrix to render it dense and non-absorbent like glass, so it is a suitable material for the disk 12. Although porcelain is fragile in thin pieces, the disk 12 is small and thick, so that it is practically unbreakable in

combination with the surrounding metal of shell 10. It also may be noted that the expansion coefficient of porcelain is about 0.000004, substantially the same as that of the borosilicate glass previously mentioned. Briefly, then, it may be 5 said that the expansion coefficient of the vitreous disk 12 is so low that the disk is practically unaffected by the working temperature of the tube. Hence, the electrodes remain in fixed relation to each other and the weld between the disk 12 10 and the fused ring 18 remains vacuum-tight. By way of example I would say that in some cases the vitreous disk 12 may be about one inch in diameter and about one fourth of an inch thick across the main part, thus giving the tube a 15 strong base which automatically insulates the lead-in wires 28 and contact pins 29 from each other across the entire distance of their spacing.

The material of the sealing ring 18 should be a glass having an expansion coefficient equal or 20 very close to that of disk 12, whether the latter be of glass or of porcelain. A glass having practically the same expansion coefficient as porcelain is readily obtainable or producible. With the members 12 and 18 having substantially the 25 same low coefficient of expansion, they become in effect a unitary base sealed to the metal shell 10. It does not matter that the expansion coefficient of the metal shell is higher than that of the glass seal 18, since the heat-insulating properties of the seal and of disk 12 prevent undue heat from reaching the flange 14 of the shell across the base of the tube. Besides, the flanged base portion of the metal shell 10 is outside the chamber of the tube and is therefore not directly 30 subject to the inside temperature. The individual seals 37' for the lead-in wires 28 are preferably 35 of glass with an expansion coefficient substantially equal to that of the wires.

The glass seals 37' will usually be made of 40 a high expansion glass (like the glass of electric light bulbs), as that gives probably the best sealing results. However, if it is found desirable in any particular instance to make the seals 37' of a low expansion glass, the wires 28 should be of metal 45 having a correspondingly low coefficient of expansion.

As an example of such metal I may mention alloys of iron and nickel having those two elements so proportioned that the expansion coefficient of the resultant alloy also represents (or closely approximates) the expansion coefficient of the glass used in seals 37'. For example, an alloy of 54% iron and 46% nickel has about the same expansion coefficient as the glass used 50 in electric light bulbs. An iron-nickel alloy known in the trade, comprising 63% iron and 37% nickel, has a coefficient of expansion so low as to be practically negligible, and in certain cases I may prefer to make the lead-in wires 28 60 of said alloy. By this I mean not only those sections of the wires that pass through disk 12, but also the upper sections to which the electrodes are secured. In Fig. 1 the grid cylinder 31 and the anode cylinder 32 are attached to rods 28' 65 which may be integral with the corresponding rods 28 or (as shown) separate pieces welded to the upper ends of rods 28. The same remarks apply to the various electrode-carrying rods in Fig. 4. Not only the rods 28-28' but also the 70 grids and the anode cylinder 32 (or 60) may be of the aforesaid iron-nickel alloy so as to remain unaffected by the temperature in the tube. That is to say, an anode consisting of a cylinder of an alloy containing approximately 63% iron and 75

37% nickel does not expand under the heat of the tube chamber and therefore does not alter its normal diameter and position relative to the enclosed grid and cathode. This fixed relationship of the electrodes at all tube temperatures is a desirable factor.

In metal radio tubes heretofore made with a shell of steel, it was found that after a while the inner surface of the steel gave off gases which deteriorated the vacuum in the tube and reduced its efficiency. As far as I know, no theory has been advanced for this phenomenon, but my study of this problem has led me to these conclusions: Commercial sheet metal, no matter how well polished or smoothed, has minute cells or pockets in its surface, due to the crystalline structure of the metal. This is particularly true of steel, which contains carbon. Also, metals take up gases in melting and doubtless very small amounts of these gases are retained in the tiny pores or cells of the solidified metal. Referring now to the metal shell of an electron tube, the multitudinous pores that happen to be on the inner surface of the shell occlude air and other gases present, and these trapped gases can not all be drawn out in the exhausting of the tube, so that they remain in the evacuated chamber. Later, during the operation of the tube, the metal gradually gives up the occluded gases which naturally vitiate the vacuum and lessen the efficiency of the tube.

I overcome the foregoing objection in prior electron tubes with a metal envelope or shell by electroplating the inner surface of the metal shell so as to fill in the air cells or pores and provide a metal surface of atomic density and smoothness substantially free of occluded gases. In the drawing the electroplated inner surface of metal shell 10 is diagrammatically indicated by numeral 40 10. The electroplating 10 may be nickel, copper, silver, chromium, and perhaps other metals found suitable for this purpose. The thickness of the electroplating should be sufficient to fill the cells or pores on the surface of shell 10 and cover it 45 completely with a uniformly smooth and dense wall of pure metal in which no gases are occluded and which prevents the escape of gases that might lurk behind the electroplating.

If the base disk 12 is made of porcelain, it may 50 be desirable in some cases to glaze its inner surface, as is usually done with porcelain. This glazing, diagrammatically indicated by numeral 71 in the drawing, is a dense vitreous coating fused to the porcelain body of the disk and performs 55 the same function as the electroplating 10 on the metal shell 10. It goes without saying that the glaze 71 should be in agreement with the thermal expansion characteristics of the porcelain used, so that no cracking of the glaze can occur. 60 If the porcelain of disk 12 contains a glassy matrix sufficiently large, the glaze 71 will not as a rule be necessary.

From what I have said it will be evident that the materials of metal shell 10, vitreous disk 12, 65 and glass seal 18 may be so chosen as to have practically the same low coefficient of expansion, so that these three parts when sealed together form in effect an integral envelope for the tube chamber. The sheet metal shell 10 can be made of an 70 iron-nickel alloy having the same expansion coefficient as the vitreous parts 12 and 18, and the inner surface of the alloy shell can be electroplated, as previously mentioned.

It is clear from the preceding description that 75 I have produced an electron discharge tube of

simple construction, easy to assemble, and one combining mechanical strength with electrical efficiency. Although I have shown and described certain specific constructions, my invention is not limited to the details set forth, for various changes and modifications are possible within the scope of the appended claims.

It is hardly needful to add that the accompanying drawing is not intended for a shop drawing and has not been made with the mathematical accuracy required in the latter. On the contrary, I have purposely exaggerated the relative dimensions of various parts for clearness.

I claim as my invention:

1. An electron tube having an outer envelope 15 consisting of a metal shell and a vitreous base within the base end of the shell, a ring separate from and between the shell and the base air-tightly uniting the shell and base, means independent of the sealing contact between said parts 20 for positively locking the base to the metal shell against axial displacement in either direction, and an electrode assembly carried by said base.

2. An electron tube having a metal shell, a base member of insulating material, a glass ring uniting 25 said base member with said shell, interlocking means on said ring and shell and base member to lock the latter against axial displacement in either direction, said interlocking means being independent of the sealing contact between the 30 shell and the base member, and an electrode assembly carried by said base member.

3. An electron tube having a metal shell, a base member of insulating material, a ring of vitreous material between and uniting the shell and the 35 base member, said shell having an inwardly turned portion locking said ring against outward axial displacement relative to the shell, and an electrode assembly carried by said base member.

4. An electron tube having a metal shell, a disk 40 comprising vitreous material, a vitreous sealing ring interposed between said shell and disk and sealed to both of said parts in wide annular contact areas, interlocking means between the shell and the ring to lock the latter against axial displacement in either direction, interlocking means 45 between the disk and the ring to lock the disk against outward axial displacement, both of said interlocking means being independent of the sealing contacts made by the ring with the shell and 50 the disk, and an electrode assembly carried by said disk.

5. An electron tube having a cylindrical metal shell provided at its lower end with an outer lateral shoulder, a flange projecting downwardly 55 from said shoulder, an insulating disk engaging said shoulder and spaced from said flange, the space between said flange and disk forming an annular recess, a fused vitreous ring filling said recess and sealed to said disk and shell, means 60 for locking said disk and sealing ring to the shell against axial displacement in either direction, said locking means being in addition to the sealing contact between said three parts, and an electrode assembly carried by said disk.

6. In the manufacture of electron tubes having a metal shell and a base disk of insulating material, the method of sealing the shell and the disk together which comprises supporting the shell 70 upside down, placing the disk on a shoulder of the shell so that an annular recess is left between the disk and the shell, placing a glass ring in said recess, which has a cross-sectional shape different from that of the glass ring, and heating the ring until it fuses and flows into the recess, whereby 75

the fused mass seals the metal shell and the insulating disk together, the cross-sectional shape of the recess causing the sealed parts to be locked together against relative axial displacement in either direction.

5. An electron tube including a cylindrical metal shell, an integral exhaust tip in the top of said shell, said tip being surrounded by an annular depression formed in the shell, and a filler in said depression to hide the tip, said filler forming a domed top for the shell.

10. An electron tube having a base disk of vitreous material relatively thick, lead-in wires passing through said disk into the tube for connection with an electrode assembly, said disk being formed with a plurality of circular recesses extending only part-way into the disk, there being a recess around each wire, and a vitreous seal filling each recess for sealing the surrounded wire 15 to the disk, each wire closing the bottom of the surrounding recess which forms a cup to hold the fused seal in place.

15. An electron tube having an envelope closed by a base disk of vitreous material formed with a plurality of recesses, said disk having an integral annular rim around each recess, a lead-in wire passing through each recess, a fused glass seal filling each recess and surrounding the associated wire which is thereby sealed to the disk in a vacuum-tight joint, the annular rim around each recess increasing the axial depth of the glass seal and the stability of the wire support, and 20 electrodes connected to said wires.

25. An electron tube having a cylindrical metal shell provided at the top with an integral metal exhaust tip which is surrounded by an annular depression in the shell, whereby said tip does not appreciably project beyond the wall surrounding said depression.

11. An electron tube having an envelope comprising a metal shell and a disk sealed to the base end of said shell, the top of said shell having a tubular projection with an opening sealed by a glass member, a lead-in wire sealed to and passing through said glass member into the envelope, a metal cap mounted over said tubular projection and insulated therefrom, said wire being connected to said cap, an electrode assembly operatively mounted in said envelope and including an element connected to said lead-in wire, and contact pins projecting from the base end of the tube and operatively connected with said electrode assembly.

15. An electron tube having a metal shell, a vitreous ring sealed to the base of said shell, a disk of low expansion glass sealed to said ring and closing the open end of said shell air-tight, said glass disk being sufficiently thick to be practically unbreakable, and an electrode assembly supported by said glass disk.

20. An electron tube having a base of insulating material, a contact pin mounted in an outer portion of said base, a lead-in wire extending from said contact pin through an inner portion of said base, said base having a recess directly around said lead-in wire, and a ring of insulating material in said recess sealed, within said recess, at its inner side to the lead-in wire and at 25 its outer side to the base to maintain the tube air-tight regardless of any air-tightness between the contact pin and the base.

25. An electron tube as set forth in claim 13 in which the contact pin has a flanged head seated in the bottom of the recess and held seated therein by the ring of insulating material.

ADOLPH A. THOMAS.
